UNITED STATES PATENT OFFICE.

RICHARD V. DE GUINON, OF BROOKLYN, NEW YORK.

ANCHOR.

Specification of Letters Patent No. 12,622, dated April 3, 1855.

To all whom it may concern:

Be it known that I, RICHARD V. DE GUINON, of Brooklyn, in the county of Kings and State of New York, have invented and made a new and useful Improvement 5 in Anchors for Vessels; and I do hereby declare that the following is a full, clear, and exact description of the construction and operation of the same, reference being had to the annexed drawing, making part of this 10 specification, wherein—

Figure 1, is a vertical section of an anchor as fitted with my improvements; Fig. 2, is an elevation endwise of the arms and flukes; 15 and Fig. 3, is a plan below the line *a*, *a*, of Fig. 1.

The like marks of reference denote the same parts.

The nature of my said invention consists 20 in providing movable flukes, constructed in such a manner that they can be attached to the ordinary anchor or to an anchor specially adapted to receive them, so as to form a concave basin of large area suitable for a 25 sandy or muddy bottom.

In the annexed drawing *b*, is the shank *c*, *c*, the arms, *d*, *d*, the flukes, *e*, the ring to receive the cable, and *f* is the stock, collectively forming an ordinary anchor.

30 1, is a collar attached to or formed with the shank near the crown, beneath which collar the straight side of each of the flukes or scoops *g*, sets, the said scoops being provided with semi circular notches to pass the 35 shank. These movable flukes *g* are to be formed of either wrought or cast iron, and of a shape to set onto and coincide with the arms *c*, and near the point of each of said movable flukes a strap or thimble 2, is provided to receive the end of the arms *c*, and connect said flukes to the arms. Whenever 40 these movable flukes are required in consequence of the sandy or muddy character of the bottom, each fluke is lowered, by means 45 of eyes or ring bolts 7, 7, onto its respective arm *c*, and the point of the arm passes into the thimble or strap 2, while the said fluke, by means of its semi circular notch passes beneath the collar 1, thereby any sea 50 striking beneath said movable flukes cannot displace the same; and in order to sustain the said movable flukes near their edges I provide joints 5, connecting tie rods *h*, *h*, to said flukes; the pair of tie rods thus connected to each fluke are united near their 55 upper ends as seen in Fig. 2, and formed

with an eye receiving a bolt 6, which bolt also passes through ears *i*, *i*, on the sides of the shank near the stock *f*, thereby connecting the sides of the movable flukes to 60 near the top of the anchor and making said flukes capable of sustaining any strain to which they may be subjected. I also provide lugs 3, 3, on the straight edges of the flukes where they come together (at right angles 65 to the arms *c*) through holes in which lugs bolts 4, 4, are passed, and retained in place by means of split keys passing through a mortise in each bolt, 4, thereby holding said movable flukes permanently to each other. 70

It will now be apparent that whenever the character of the bottom, or the force of a gale renders it probable that a vessel will drag the ordinary anchor that these movable flukes should be attached in their place and 75 when in use will take hold of such a mass of sand or mud as effectually to prevent the anchor being dragged; and it will also be apparent that the additions made to the ordinary anchor to allow of these movable flukes 80 being attached, do not interfere with the efficiency of the anchor when used without said movable flukes.

When the anchor is to be heaved, or hoisted in, a chain attached to the eye 8, should 85 first be heaved on, which lifting the crown of the anchor discharges all the sand or mud which would otherwise be lifted in the anchor flukes *g*, *g*. If found necessary projections may be formed on the convex sides 90 of the movable flukes to set on each side of the arms *c*, to guide and steady the flukes when being lowered down into place.

I do not claim fitting an anchor so as to hold in mud or sand by providing either 95 large fixed or movable flukes in themselves but

What I desire to secure by Letters Patent is—

I claim the method herein described of 100 fitting a pair of movable flukes (*g*) to a suitable anchor, so as to fit it to hold in soft or sandy soil, by means of the tie rods *h*, thimble 2, and collar 1; for the purposes and as specified. 105

In witness whereof I have hereunto set my signature the 10th March 1855.

R. V. DE GUINON.
